UNITED STATES PATENT OFFICE.

CLAUDE J. ELLIS, OF LIBERTY, TENNESSEE.

GATE MECHANISM.

1,249,051.

Specification of Letters Patent. Patented Dec. 4, 1917.

Application filed May 2, 1914. Serial No. 835,943.

To all whom it may concern:

Be it known that I, CLAUDE J. ELLIS, a citizen of the United States, residing at Liberty, in the county of Dekalb and State of Tennessee, have invented certain new and useful Improvements in Gate Mechanism, of which the following is a specification.

My invention relates to improvements in gates.

10 The invention aims to provide an effective and desirable form of gate that may be used especially as a farm gate and be operable so as to completely expose the gate-way when desired and be operable from either 15 of its sides from a distance.

One object of the invention is to provide an improved form of fastening means co-operating with a vertically movable gate, and with means whereby the fastening 0 means may be simultaneously unlocked through the operation of said means for raising the gate.

Another object of the invention is to provide a construction wherein the parts may 25 operate without undue friction and the chains employed be accommodated for effective operation.

Further objects of the invention are to 30 provide an improved form of fastening for the latch, keeper means for the latch, and means whereby the gate may be assisted in its movement to open position.

With the foregoing and additional objects in view, such as will appear herein- 35 after from the description following taken in connection with the accompanying drawings, the invention has been embodied in preferable form, in the device illustrated in said drawings.

40 In said drawings:—

Figure 1 is a front elevation of the gate and its coöperating mechanism;

Fig. 2 is an end view of the same parts;

Fig. 3 is a plan view of the gate and parts 45 mounting it;

Fig. 4 is a detail side elevation of the latch and

Fig. 5 is a detail view illustrating the joints of the operating chain.

50 Referring specifically to the drawings. A generally designates a gate, the particular construction of which is immaterial except for the performance of the functions hereinafter described. As shown, this gate has

55 a plurality of longitudinal bars 1 joined by vertical end bars 2 and intermediate verti-

cal bars 3 and 4, and braced by diagonal bars 5. At the rear, the gate is mounted between two posts 6 and at its lower rear end is pivoted to said posts by means of a 60 bolt 7 extending through the gate and said posts. The gate at its forward end extends between two spaced posts 8 bridged by a latch keeper 9 which will be hereinafter referred to. 65

The fastening member employed is in the form of a slidable latch, specifically illustrated in Fig. 4. This latch has enlarged ends 10 connected by an intermediate reduced bar or shank 11. The shank 11 is 70 slidably mounted between the vertical bars 3 and the latch as a whole is slidably mounted between two of the longitudinal bars 1 and the front guide bars 2, projecting slightly beyond the same so as to engage 75 beneath the keeper 9. The spring 12 surrounds the shank 11, is fastened to the latch and to one of the bars 3, urging the latch toward the keeper.

While the latch may be operated in any 80 suitable manner, yet I prefer to provide means whereby upon operation of a single member, the latch will be shifted and the gate simultaneously swung vertically from its pivot 7. To this end operating levers 13 are provided and pivoted to vertical posts 14 at 15. It is clear that any suitable means 85 may be provided to connect the levers 13 with the latch. As to the specific form of means shown in the drawings, a clevis 16 is 90 pivoted at 17 to the latch adjacent its rear end. A ring or link 18 is carried by the clevis and to this ring is fastened a short flexible element in the form of a chain 19 movable in the grooved periphery of a roller 20 mounted between the bars 4 and therefrom by means of a pin 21. Beyond the roller, to chain 19, chains 22 are fastened, one leading to each lever 13 and passing through the eyes 14' thereof. Chains 22 are 95 located on opposite sides of the gate and are normally held taut by the spring 12 and the levers 15. To each of the chains a short chain 23 is fastened, which short chain is also fastened in eye 24 of one of the 100 diagonal braces 5 and are normally slack, as shown in Fig. 1. The levers 13 if desired 105 may have pendant operating handles 25 connected thereto by means of flexible chains or the like 26.

Beneath the gate is preferably provided a sill 27, made for instance of concrete, and 110

from which sill as a foundation, the posts 6 and 8 rise. Posts 6 and 8 are preferably reduced and curved outwardly at their tops at 28, in order to guide the gate between the 5 posts properly, should the same move laterally in operation. Also in order to provide sufficient space for operation of the chains 22, between the posts 6, spacing disks 29, one on each side of the gate, may be mounted on the bolt 7 intermediate the 10 posts 6.

In order to better balance the gate A so as to facilitate operation to open position, a suitably shaped weight 30 may be provided at its top over the pivot 7.

In order to operate the gate, either of the handles 25 is pulled downwardly, whereupon the lever 13 shifts from its pivot 15 pulling chains 22 and 19, and in turn pulling or sliding the latch against the tension of spring 12, thereby disengaging the latch from the keeper 9 and causing the chain 23 to become taut. By further pull on the same handle, the chain 23 will become effective and the gate will move vertically about its pivot 7 until the end bars 2 at the pivot will rest directly on the ground and the gate be in a position at right angles to the position shown in Fig. 1. This movement is assisted by the weight 30. From the foregoing it will be seen that when either of the levers 15 is operated, it causes the respective chain 22 to first move the latch 10 to its inoperative position and, at 35 the same time, to make said chain 23 taut, thereby rendering the latter effective for swinging the gate upward when the lever 15 continues its movement. Therefore, the latch is not subject to any strain except that which is necessary to overcome the tension of the spring 12 and to overcome the friction of said latch against the keeper and the bearing portion of the gate. When the gate is lowered, its weight is sufficient to 40 cause the latch 10, by engagement of its deflected face, as provided at 31, to engage the

keeper 9 and move past the same until the gate is in closed position whereupon spring 12 which has been retracted by such action, will urge the latch beneath the keeper 9 into 50 the position shown in Fig. 1. It will be realized that the roller 20 provides a means whereby the chains may operate without undue friction and that said chains may effectively operate between the gate and the 55 posts 6 due to the provision of the spacing disks 29.

It is to be understood that I have shown merely the preferred form of my invention and that I do not limit myself to such form 60 as the same can be varied without departing from the spirit and scope of the invention.

I claim—

A gate comprising a support, a gate frame 65 pivotally mounted on said support, a latch movably mounted on said gate frame, a spring for holding said latch in its operative position, operating means carried by said support, a flexible element connecting said latch with said operating means and thereby operable to move said latch to its inoperative position, said flexible element being normally held taut by said spring and by said operating means, and a flexible element connected to the first said flexible element and to said gate frame and being normally slack and adapted to be made taut by operation of the first said flexible element when the latch has been moved to its inoperative position, 70 whereby said operating means first moves said latch to its inoperative position and thereafter effects the upward movement of the gate independent of greater strain on said latch than is necessary to move the latter to its inoperative position.

In testimony whereof I affix my signature in presence of two witnesses.

CLAUDE J. ELLIS.
